UNITED STATES PATENT OFFICE.

ROBERT C. STUBBS, OF DALLAS, TEXAS.

PAVING FOR STREETS AND THE LIKE.

1,315,749.

Specification of Letters Patent. Patented Sept. 9, 1919.

Application filed September 14, 1916. Serial No. 120,004.

To all whom it may concern:

Be it known that I, ROBERT C. STUBBS, a citizen of the United States, residing at Dallas, in the county of Dallas and State of 5 Texas, have invented certain new and useful Improvements in Paving for Streets and the like, of which the following is a specification.

My invention relates to street and other 10 paving, and the object is to provide paving with certain constructions which will be highly efficient in resisting wear and which can be laid at a reasonable cost. Another object is to provide a paving which can be 15 re-surfaced at small cost and to provide a wearing surface which will protect the main body of the paving slab from the deleterious effects of changes in the weather while the slab is in a state of curing as well as protecting the slab from the effects of traffic. 20 The improved paving is made capable of sustaining heavy traffic by the process set forth in the patent granted to me on April 13, 1909, No. 918,388. Other objects and 25 advantages will be fully explained in the following description and the invention will be more fully pointed out in the claims.

Reference is had to the accompanying drawings which form a part of this application.

Figure 1 is a vertical section of a section of paving, showing the condition of the materials as the paving is just being completed. Fig. 2 is a vertical section of a completed section of paving.

Similar characters of reference are used to indicate the same parts throughout the several views.

The paving is illustrated in the drawings 40 as being laid on the surface of graded earth 1. Concrete is prepared in the usual manner with cement, sand, stone, and water, but with an increase in cement, sand and water in order to provide a slight surplus 45 of mortar. A concrete slab 2 is formed on the grade 1 by placing thereon enough plastic concrete to make a paving of the desired thickness. After the plastic concrete is laid, and before the concrete is cured 50 or becomes hard or set, a wear resisting surface is formed by placing additional stone or crushed granite 3 on the upper surface of the concrete and then forcing the additional stones down into the plastic concrete 55 by placing thereon a platform and then vi-

brating the stones 3 and the whole slab of concrete with pressure, as set forth in the above noted patent until the stones are sunk into the surface of the concrete. More or less pressure can be used but the vibration 60 and pressure must be simultaneously applied. The slab is then ready to be cured. In order that the curing may not be interfered with, a wearing coating 4 is placed on top of the slab 2 to protect the slab from 65 the wear of the traffic or travel while being cured and also to prevent heat or cold from interfering with the curing of the slab, and preventing the moisture from escaping from the interior of the mass. The coating or 70 wearing surface 4 may be thick enough to last several years. By the time the surface 4 is worn off, the concrete slab will be thoroughly cured and the slab will have a smooth hard surface composed of the stones embedded in the concrete. The stone will be 75 so embedded in the concrete and the concrete will be so crystalized about the stone that the stone and concrete will be as one material and will form a surface that will be strong 80 enough to resist the heaviest traffic and will resist wear so that the life of the paving will be prolonged. A surface will also be formed upon which a new wearing surface may be placed at very small cost. Thus a slab is 85 formed which may be used simply as a substratum or which can be used as the surface paving. It may be used a sub-stratum and recovered with a wearing surface of 90 bituminous or asphaltic consistency. Concrete will not reach its full power of resistance until several months, and when used for street paving, must be given every possible advantage and protection before it is exposed to the severe test of active traffic. 95 The surface coat 4 answers the purpose of protecting the new laid concrete.

What I claim, is:-

1. The herein described method of forming paving which consists in laying concrete 100 on a prepared sub-grade, placing of stones on the surface of said concrete, and forcing the same by vibration and pressure into said concrete while the concrete is in plastic condition for causing the stone to become an 105 integral part of the mass.

2. The herein described method of forming paving for streets and like purposes which consists in laying concrete containing a surplus of mortar on a prepared sub- 110

grade, placing stones on the surface of the concrete and forcing the same down by vibration and pressure simultaneously applied into the concrete immediately after the concrete is laid thereby forcing the surplus mortar out of the concrete and forcing the stones in close relation.

3. The herein described method of forming paving for streets and like purposes which consists in laying concrete containing a surplus of moisture on a prepared sub-grade, placing stones on the surface of the concrete and forcing the same by vibration and pressure down into the concrete immediately after the concrete is laid thereby forcing the surplus mortar out of the concrete, and forming a moisture proof

surface course by the addition of surface forming material.

4. The herein described method of forming paving for streets and like purposes which consists in laying concrete containing a surplus of mortar on a prepared sub-grade to form a slab, placing stones on the surface of the concrete and forcing the same down therein by vibration and pressure immediately after the concrete is laid, causing the mortar of the concrete to be compacted on all the surface of each stone for creating a permanent wearing surface. 25

In testimony whereof, I set my hand, this 9th day of September, 1916. 30

ROBERT C. STUBBS.
